INSEAM SHOE SEWING MACHINE

Andrew Eppler, Lynn, Mass., assignor to United
Shoe Machinery Corporation, Paterson, N. J.,
a corporation of New Jersey

Application October 24, 1933, Serial No. 694,955

12 Claims. (Cl. 112—47)

This invention relates to improvements in inseam shoe sewing machines, and is herein set forth as embodied in a machine similar in many respects to that illustrated and described in the 5 United States Patent No. 1,507,885 granted to the present inventor, September 9, 1924.

In the machine described in the patent, the work is fed in two separate steps, each of one half the length of a stitch, so that the work feeding 10 instruments will engage the work a distance from the needle less than the length of a stitch. This arrangement is an improvement over previous machines in sewing around pointed toes because the work engaging instruments having smaller 15 separation in the line of feed offer less resistance to turning.

The principal object of the present invention is to provide a machine in which the work feeding instruments will so operate as to retain the advantages of easy sewing on pointed toed shoes and, 20 at the same time, furnish more effective support against the penetrating stroke of the needle for thin materials likely to be employed in such shoes, and particularly in shoes having canvas 25 covered insoles.

With this object in view, a feature of the present invention contemplates the provision in an inseam shoe sewing machine of a feed point and a channel guide operating to feed the shoe 30 with a multiple step movement and in such a way that the feed point will support the shoe between the needle and the last formed stitch while the needle engages the work. In order to support the work at the other side of the needle in the present embodiment of the invention, the channel guide is moved close to the point where the needle emerges and is back fed away from the needle 35 out of the path of the looper in laying the thread in the needle barb. To prevent the feed point 40 from impinging on the threads of a stitch being set, the feeding movements of the feed point, in the machine illustrated, are made unequal, the back-feeding movement corresponding in length to the longer feeding movement, taking place 45 while the needle is withdrawing with the threads.

These and other features of the invention, certain of which are not limited to a construction in which a plurality of feeding movements are imparted to the feed point during each stitch 50 forming cycle, will be readily understood from an inspection of the accompanying drawings and the following detailed description illustrated therein.

In the drawings, Fig. 1 is a view in front elevation showing so much of an inseam sewing ma-

chine as is necessary to illustrate the preferred form of the invention; Fig. 2 is a side elevation on a somewhat reduced scale of the machine illustrated in Fig. 1; and Figs. 3 to 9, inclusive, are diagrammatic views indicating the mode of operation of the stitch forming and work supporting devices of the machine.

The machine illustrated in the drawings is a welt and turn shoe sewing machine having the same general construction as the machine shown 10 and described in inventor's Patent No. 1,108,560 dated August 25, 1914. The machine is provided with a curved hook needle 2, a looper 4, a thread arm 6, a feed point 8, a channel guide 10, a back gage 12, and a back rest 14, all of which are similar in construction to the corresponding parts in the machine of Patent No. 1,108,560, with the exception of the feed point which, in the present machine is formed with a work guiding surface 15 similar to that at the end of the channel guide 20 and with a sticker point projecting from the end to prevent slipping when in engagement with the work.

In the present machine the feed point and the channel guide are so mounted that they are independently movable in the line of feed and the feed point is operated to give two feeding movements to the work between successive work piercing strokes of the needle. One of the feeding movements of the feed point is greater than another during each cycle of the machine, a back-feeding movement corresponding in length to the greater feeding movement taking place after the needle has engaged the work to insure that the feed point will not impinge upon the thread being drawn through the work by the needle. The greatest distance between the needle and the feed point while in engagement with the work is, therefore, less than the length of a stitch, thus permitting easier turning of the shoe when sewing about 35 the toe portion.

In the construction shown, the feed point is mounted on a carrier segment 16 which is oscillated by a cam operated lever 18 towards and from engagement with the insole channel. The 45 segment 16 is pivotally mounted upon a feed slide 20 and is reciprocated in the line of feed by a cam roll 22 on the feed slide, engaging a cam groove formed in a rotating disk 24.

The channel guide is secured upon a lever 26 50 mounted to rock and to slide in the direction of feed upon a stud 28 secured to the feed slide 20. The lever 26 is rocked to move the channel guide towards and from the work by a cam operated arm 30 engaging the lever and is moved in the 55

line of feed by a cam lever 32 provided with a tooth space engaged by a tooth on the hub of the lever 26.

The work is fed through the machine almost entirely by the operation of the feed point which imparts successively a short movement and a longer movement during each cycle of the machine. Before the longer back-feeding movement of the feed point, the channel guide is also back fed a short distance in order to provide more space about the end of the needle for passage of the looper. The feed point is then given its greatest back-feeding movement, after which it engages the work and feeds it forward a short distance, back-feeding a similar distance thereafter, while the channel guide remains stationary. The feed point and channel guide then move together to feed the work into the proper position to be engaged by the needle. After the final work feeding stroke in each stitch, the feed point and channel guide are located one on each side of the needle path as it emerges from the work, the feed point engaging the channel between the needle and the last formed stitch to give ample support for the material operated upon.

The position of the parts upon reaching this point in each cycle of the machine is illustrated in Fig. 3 which shows the needle about to engage the work. In ordinary inseam sewing machines, the needle in passing through the work may deflect the material forming the channel flap, indicated at 34, as the point passes through the upper 36. This will cause the channel flap to be bent forward and result in failure to form a secure stitch or other difficulty. With the use of a canvas covered insole, the needle may successfully pass through the insole flap but may cause the canvas to separate from the insole along the channel. In the present machine the channel flap, being supported at both sides of the needle, as indicated in Fig. 4, the needle will pass through all of the materials operated upon in a reliable manner.

As soon as the needle has reached the end of its penetrating stroke, the feed point moves away from the work and the channel guide is back fed to the position of Fig. 5 to permit the looper to pass about all sides of the needle. The needle is then retracted with the new loop of thread and the feed point, having been back-fed, engages the work between the channel guide and the hole formed by the needle, as in Fig. 6. Figure 7 shows the work after having been moved in the direction of feed by the feed point a distance shorter than the previous back-feeding movement, after which the feed point is retracted from the work and again back-fed a distance equal to said previous feeding movement, the channel guide having remained stationary. This position is illustrated in Fig. 8, from which position the feed point and channel guide move together in a direction of feed to the position of Fig. 9. The feed point in this last feeding movement moves a greater distance than in the shorter feeding movement and also a greater distance than the channel guide, so that the proper space is provided between the two instruments to accommodate passage of the needle. The cycle of movements is then repeated as the machine continues in operation. The feed point thus gives the work two feeding steps of less than the length of each stitch while the channel guide moves in the line of feed away from the needle a distance also less than the length of a stitch, furnishing proper

support to the work as well as permitting easy manipulation in operating upon pointed shoes.

The nature and scope of the invention having been indicated, and a particular embodiment of the invention having been specifically described, what is claimed is:

1. An inseam shoe sewing machine having, in combination, stitch forming and work supporting devices including a curved hook needle, a feed point and a channel guide, and mechanism for actuating the feed point to support the work against the penetrating stroke of the needle between the needle and the last formed stitch and successively to feed the work in each stitch forming cycle through a plurality of feeding movements. 15

2. An inseam shoe sewing machine having, in combination, stitch forming and work supporting devices including a curved hook needle, a looper, a feed point and a channel guide, and mechanism for actuating the needle to penetrate the work while the feed point remains in engagement with the work at one side of the needle and for actuating the feed point to impart two separate feeding movements to the work during each 25 stitch forming cycle of the machine.

3. An inseam shoe sewing machine having, in combination, stitch forming and work supporting devices including a curved hook needle, a looper, a feed point and a channel guide, and mechanism 30 for actuating the needle to penetrate the work while the feed point and the channel guide remain in engagement with the work and for actuating the feed point through two separate back feeding movements and the channel guide 35 through a single back feeding movement during each stitch forming cycle of the machine.

4. An inseam shoe sewing machine having, in combination, stitch forming and work supporting devices including a curved hook needle, a 40 looper, a feed point and a channel guide, and mechanism for actuating the feed point and the channel guide in the direction of feed to support the work at either side of the needle as the needle penetrates the work and for actuating the 45 channel guide away from the needle before the looper lays the thread in the needle barb.

5. An inseam shoe sewing machine having, in combination, stitch forming and work supporting devices including a curved hook needle, a 50 looper, a feed point and a channel guide, and mechanism for actuating the feed point and the channel guide in the direction of feed to support the work at either side of the needle as the needle penetrates the work and for actuating the 55 feed point out of engagement with the work and the channel guide in the line of feed away from the needle before the looper lays the thread in the needle barb.

6. An inseam shoe sewing machine having, in 60 combination, stitch forming and work supporting devices including a curved hook needle, a feed point and a channel guide and mechanism for actuating the feed point successively while engaging the work through feeding movements of 65 unequal lengths in each stitch forming cycle of the machine.

7. An inseam shoe sewing machine having, in combination, stitch forming and work supporting 70 devices including a curved hook needle, a feed point and a channel guide and mechanism for actuating the feed point successively while engaging the work through feeding movements of 75 unequal lengths in each stitch forming cycle of the machine and for actuating the channel guide

- in the direction of feed with a single feeding movement during each cycle.
8. An inseam shoe sewing machine having, in combination, stitch forming and work supporting devices including a curved hook needle, a feed point and a channel guide and mechanism for actuating the feed point successively while engaging the work through movements of unequal lengths in each stitch forming cycle of the machine and for actuating the channel guide in the direction of feed with a single feeding movement, simultaneously with one of the movements of the feed point while engaging the work.
9. An inseam shoe sewing machine having, in combination, stitch forming and work supporting devices including a curved hook needle, a feed point and a channel guide and mechanism for actuating the feed point successively while engaging the work through feeding movements of unequal lengths in each stitch forming cycle of the machine and for actuating the channel guide in the direction of feed with a single feeding movement of shorter length than and simultaneously with the greater movement of the feed point while engaging the work.
10. An inseam shoe sewing machine having, in combination, stitch forming and work supporting devices including a curved hook needle, and mechanism for actuating the work supporting
- devices against the side of the work opposite the needle at both sides of the needle while the needle pierces the work and for actuating the supporting devices in the line of feed to prevent engagement with the work at a distance from the needle greater than the length of a stitch.
11. An inseam shoe sewing machine having, in combination, stitch forming and work supporting devices including a curved hook needle, a feed point and a channel guide, and mechanism for actuating the feed point and channel guide against the side of the work opposite the needle at the sides of the needle while the needle pierces the work and for actuating the channel guide in the line of feed a distance from the needle less than the length of a stitch.
12. An inseam shoe sewing machine having, in combination, stitch forming and work supporting devices including a curved hook needle, a looper, a feed point and a channel guide, mechanism for actuating the needle to penetrate the work while the feed point remains in engagement with the work at one side of the needle, a support for the channel guide to permit movement in the line of feed relative to the feed point, and mechanism for actuating the channel guide in the line of feed away from the needle before the looper lays the thread within the needle barb.

ANDREW EPPLER.
